(57) CLAIM

The ornamental design for a head protector, as shown and described.

DESCRIPTION

FIG. 1 is a rear perspective view of a head protector in accordance with the present invention;

FIG. 2 is a left view thereof;

FIG. 3 is a right view thereof;

FIG. 4 is a front view thereof;

FIG. 5 is a back view thereof;

FIG. 6 is a top view thereof;

FIG. 7 is a bottom view thereof; and,

FIG. 8 is a perspective view of the head protector shown in a position of use inside the liner of a hat.

The broken lines in the drawings depict portions of the head protector that form no part of the claimed design. In FIG. 8, the broken lines depicting a liner of a hat represent environmental subject matter that forms no part of the claimed design.

1 Claim, 7 Drawing Sheets
